(57) **CLAIM**

The ornamental design for door handle, as shown and
described.

DESCRIPTION

FIG. 1 is an exploded bottom view of one embodiment of a
door handle showing my new design;

FIG. 2 is a second embodiment of a bottom view of a grip
for a door handle of FIG. 1 shown separately for purposes
of illustration;

FIG. 3 is third embodiment of a bottom view of the grip for
a door handle of FIG. 1 shown separately for purposes of
illustration;

FIG. 4 is a front exploded view of the door handle of FIG.
1;

FIG. 5 is a back exploded view of the door handle of FIG.
1, the only difference being the interchangeable grip;

FIG. 6 is a front view of the door handle of FIG. 1 in an
alternate position, the only difference being the interchangeable
grip;

FIG. 7 is an exploded front elevational view of a door handle
of FIG. 1 with the interchangeable grip detached for pur-
poses of illustration, the only difference being the inter-
changeable grip;

FIG. 8 is a front elevational view of one embodiment of the
interchangeable grip of the door handle shown separately for
purposes of illustration;

FIG. 9 is an exploded rear elevational view of one embodi-
ment of a door handle with interchangeable grip detached
for purposes of illustration, the only difference being the
interchangeable grip; and,

FIG. 10 is a rear elevational view of one embodiment of the
interchangeable grip for a door handle shown separately for
purposes of illustration.

The broken lines are included for the purpose of illustration
and form no part of the claimed design.
